THERMOPILE STRUCTURE

Laurenee C. Biggle, Altadena, Calif., assignor to
 General Controls Co., Glendale, Calif., a corporation of California

Application February 18, 1952, Serial No. 272,055

6 Claims. (Cl. 136—4)

1

This invention relates to thermoelectric devices of the type adapted, when heated by a small flame such as that produced by an ordinary fuel-gas pilot burner, to generate electric energy in an amount sufficient for operative energization of sensitive electric control devices such as pilot valves, switching devices, and the like; such generating devices comprising a thermocouple, or a plurality of thermocouples electrically interconnected in series to form a thermopile. The present invention is, in some respects, an improvement on the invention disclosed in Patent No. 2,526,112.

An object of this invention is to provide a novel thermopile of the character described, and a protective sheath therefor.

Another object is to provide improved and simplified means for so mounting the thermopile in the sheath that the hot junctions of the thermopile are maintained in good thermal-transfer relation to the sheath.

For full understanding of the invention, and further appreciation of its features and advantages, reference is to be had to the following detailed description and accompanying drawing, and to the appended claims.

In the drawing:

Figure 1 is a longitudinal sectional view of a thermopile structure embodying this invention; the thermopile unit 17—18 being shown in elevation;

Figure 2 is a transverse section, to enlarged scale, taken along the line 2—2 of Fig. 1; and

Figure 3 is an elevational view of the thermopile unit per se.

In the drawing, the numeral 11 indicates a sheath having an upper section 12 of thin corrosion-resistant metal such as stainless steel, the side wall of this section being circular in cross-section and tapering inwardly in a direction toward its top where it is provided with an integral flat end-wall 13. The upper section 12 is joined at its bottom, as by welding, to a generally cylindrical lower section 14 which serves as a base for supporting the structure in a gas-burner device, such as is shown in the aforementioned Patent No. 2,526,112, whereby the top portion of the structure may be heated; a groove 15 being provided in the periphery of the lower section for fastening means such as a snap-ring or the tip of a set-screw.

Within the sheath 11 is a thermopile unit which is shown per se in Fig. 3 and comprises a plurality (four, as shown) of thermocouples 16 each of which is formed by a pair of conductors

2

17—18 joined together, as by welding, at their upper ends; these conductors being of thermoelectrically dissimilar metals such as an alloy (known as "Copel") containing approximately 55% Cu and 45% Ni and another alloy (known as "Chromel," adapted for use in conjunction with "Copel") containing approximately 99% Ni and 10% Cr; the thermocouples being interconnected at their lower ends in electrical series to form the thermopile.

The conductors 17—18 are ribbon-like; their width and thickness in an actual embodiment of the invention being 0.093 inch and 0.014 inch respectively. The tops 19 of the thermocouples are conveniently considered as the hot junctions of the thermopile unit since the temperature of the unit, when in operation, is the highest at those ends which are arranged in a common plane and are in virtual engagement with the end wall 13 of sheath 11, from which they are electrically insulated by a thin disk 20 of mica.

The thermopile conductors are electrically insulated from each other by films of oxide formed on them by subjecting the unit, before assembly in the sheath, to high temperature in an oxidizing atmosphere; such insulation being sufficient to withstand the low voltage involved which, in normal operation, is about 100 mv. across the whole four-couple thermopile when the same is constructed of the alloys mentioned.

Around each of the end conductors of the thermopile unit is a thin sleeve 21 of material woven from glass fiber which protects the oxide film on these conductors from abrasion and provides additional electrical insulation between the conductors and the sides of the sheath section 12 adjacent its upper end, as can be seen in Fig. 2; the sleeves 21 also serving an additional purpose to be described.

For the sake of clarity the thermopile unit is shown in expanded condition in Fig. 3. Before it is inserted in the sheath the unit is lightly wrapped with fine glass-fiber thread (not shown) which holds the conductors together temporarily; a pile 22 of the glass thread being formed around the lower end of the unit to centralize that end within the sheath.

A pair of copper wires 23 are welded to the outer conductors of the thermopile and extend from the bottom of the sheath, within flexible armor 24, for connection to an electrical device to be energized; a strip 25 of electrical insulating material being inserted between the inner ends of wires 23. The intermediate ones of conductors 18 are extended downwardly, as indicated at 26

in Fig. 3, to aid dissipation of heat from the cold junctions at the lower end of each of the thermocouples.

The upper sheath-section 12 is so tapered, or constricted at its upper end, as to grip the side corners of the thermopile unit when, in assembly of the structure, the unit is pressed into final position in the sheath with the hot-junction ends 19 of the unit in virtual engagement (through mica disk 20) with the end wall 13 for effective transfer of external heat through the sheath to the unit. The material of the sheath-section 12 is resilient and so thin (0.007 inch in an actual embodiment) that the circular side wall of the sheath is easily deformed by the rectangular end of the unit to ensure frictional holding in place of the unit. The glass-fibre sleeves 21 also contribute to the gripping effect since they are somewhat elastic and their upper ends bear against the sides of the sheath at points below the top of the sheath (see Fig. 2) at which points the structure is relatively yieldable.

After the thermopile unit is in place, the lower interior of the sheath is filled with a thermosetting material, indicated at 27, which hermetically seals the structure and serves as additional support for the inner parts; the material being of a type adapted to withstand the temperatures involved and to adhere tightly even to the smooth inner surface of the sheath, the material being known in the art as glass sealing compound. Even although the thermocouple elements or conductors are already oxidized, it is advisable to prevent further oxidation (particularly of the "Copel" elements) by providing the hermetic seal. It is to be observed that after the thermopile unit (with cable 23-24 attached) is inserted in the sheath and forced to final position with its hot-junction ends 19 in tight engagement with the end wall 13, the only step remaining for completion of the structure is the sealing of the open end of the sheath.

The specific embodiment of my invention herein shown and described is susceptible of modification without departing from the spirit of the invention, and I intend therefore to be limited only by the scope of the appended claims.

I claim as my invention:

1. In a thermopile structure: an elongated unit, generally rectangular in cross-section, comprising a plurality of ribbon-like conductors arranged with their sides in abutting relation and their ends terminating generally in a plane at one end of the unit, said conductors being alternately of thermoelectrically dissimilar metals and interconnected electrically to form a thermopile having its hot junctions at said one end of the unit; and a sheath enclosing said unit and having an end wall engaged by said hot-junction end of the unit, the portion of said sheath adjacent said end wall being generally circular in cross-section and of thin resilient material having good thermal conductivity, said sheath-portion being constricted so as to grip the side corners of the unit and thereby frictionally maintain the unit with its hot-junction end in engagement with the end wall.

2. In a thermopile structure: a plurality of flat ribbon-like conductors arranged with their sides in abutting relation to form an elongated unit generally rectangular in cross-section and with the ends of the conductors terminating in a plane at one end of the unit, said conductors being alternately of thermoelectrically dissimilar metals and interconnected electrically to form a thermopile having its hot junctions at said one end of the unit; and a sheath enclosing said unit, said sheath having, in a plane at right-angles to its longitudinal axis, a flat end-wall engaged by said hot-junction end of the unit, the portion of said sheath adjacent said end wall being generally circular in cross-section and of thin resilient material having good thermal conductivity, said sheath-portion being constricted so as to grip the side corners of the unit and thereby frictionally maintain the unit with its hot-junction end in engagement with the end wall of the sheath.

3. A thermopile structure as defined in claim 2, and wherein the side walls of said sheath-portion taper inwardly in a direction toward said end wall and so as to grip the side corners of said unit tightly when said hot-junction end of the unit is in engagement with the end wall.

4. In a thermopile structure: a plurality of flat ribbon-like conductors arranged with their sides in abutting relation to form an elongated unit generally rectangular in cross-section and with the ends of the conductors terminating in a plane at one end of the unit, said conductors being alternately of thermoelectrically dissimilar metals and interconnected electrically to form a thermopile having its hot junctions at said one end of the unit, said unit having a symmetrically-arranged lateral enlargement of its side corners adjacent to but spaced longitudinally from said hot-junction end of the unit and a sheath enclosing said unit, said sheath having, in a plane at right-angles to its longitudinal axis, a flat end-wall engaged by said hot-junction end of the unit, the portion of said sheath adjacent to said end wall being generally circular in cross-section and of thin resilient material having good thermal conductivity, the side walls of said sheath-portion tapering inwardly in a direction toward said end wall and being arranged so as to tightly grip the corners of said unit-enlargement when said hot-junction end of the unit is in engagement with the end wall of the sheath.

5. A thermopile structure as defined in claim 4, and wherein said unit-enlargement is formed by elastic electrical insulating material.

6. A thermopile structure as defined in claim 4, and wherein said unit-enlargement comprises a sleeve of electrical insulating material encircling a portion of each of the end conductors of said unit.
